APPARATUS FOR PLACING EXPLOSIVES

Filed Nov. 3, 1939

UNITED STATES PATENT OFFICE

2,281,103

APPARATUS FOR PLACING EXPLOSIVES

Gordon C. MacDonald, Tulsa, Okla., assignor to
 Gulf Oil Corporation, Pittsburgh, Pa., a corporation of Pennsylvania

Application November 3, 1939, Serial No. 302,757

5 Claims. (Cl. 102—4)

This invention or discovery relates to apparatus for placing explosives, and it comprises an apparatus for placing a charge of explosive at any desired level in a well, including an explosive container, cable means for lowering the container in a well, electrically operable releasing means associated with the container and adapted upon operating thereof to release the explosive in the well, and means for applying electrical energy to said releasing means; all as more fully hereinafter set forth and as claimed.

In the oil production art it is often desirable or necessary to shoot a well, after drilling is completed, to shatter the rock surrounding the well bottom and thereby open up channels for the oil. For this purpose heavy charges of nitro-glycerine are ordinarily used. These are deposited in the well and exploded by a time bomb or other suitable means. The present apparatus for placing the explosive permits lowering a container shell of explosive to the bottom with the aid of a hook or similar attachment which releases the shell automatically when the shell reaches the bottom of the well and takes the weight of the shell off the hook. Ordinarily several shells are used, lowered successively one on top of another. Sometimes the explosive is lowered in a dump shell and is released directly into the well. In practice, the releasing mechanism sometimes fails to function, which necessitates raising the loaded shell and making adjustment. This is dangerous especially when the explosive has been subjected to high temperatures in the lower part of the well, thereby making it more sensitive to shock. Also there is considerable strain put upon the reel, lowering line, etc.

On the other hand, in this conventional system the shell is often released prematurely. Since the arrangement is such that the shell is released upon any bottom contact such as to relieve the weight on the releasing mechanism, the explosive may become released at the wrong place by the shell striking floating or suspended material in the bore liquids. Sometimes the bore walls cave after a portion of the explosive has been placed, and the first evidence of this is the impact of the subsequent shell upon the caved material with resulting deposition of the explosive at that point. Removal is hazardous.

Similar considerations apply to the dump shell explosive-placement system, with even greater force, since once the explosive is released from the shell, it cannot be recovered.

The present invention is based on the discovery that by a suitable electrical control, actuatable

from the top of the well, explosive can be released at any desired level in a well and premature release can be obviated.

Among the objects of the present invention are the provision of an improved apparatus for placing explosive at a desired level in a well, in which release of explosive is accomplished under a positive electrical control, and the provision of such apparatus in which accidental release of explosive at a level above the desired level is made impossible.

The invention can be embodied in two principal forms, adapted for release of a shell of explosive, and for release of free explosive into the well. 15 The apparatus includes an electrically actuatable releasing device, arranged for lowering into a well on a cable and, upon actuation, to release either a shell of explosive, or a charge of free explosive as the case may be. Electrical means 20 are provided at the surface for operating the release. Means are provided for positively retaining the explosive charge until the electrical release is actuated.

In the accompanying drawing there are shown 25 diagrammatically several examples of specific embodiment of apparatus within the purview of the invention and adapted for the performance of the method. In the drawing,

Fig. 1 is a diagrammatic view of the complete 30 apparatus as set up at a well,

Fig. 2 is a detail view in central vertical section, with some parts shown in elevation, of one form 35 of explosive shell releasing means,

Figs. 3 and 4 are similar views of two modified forms of the apparatus of Fig. 2,

Fig. 5 is a similar view of an apparatus designed 40 for release of free explosive, and

Fig. 6 is a similar view of a modified form of the apparatus of Fig. 5.

45 In the drawing, in which like reference characters indicate like parts, Fig. 1 shows one form of the apparatus installed in a well 10 provided with a casing 11. According to the invention there is provided a container shell 12 adapted to contain a charge of explosive 13, usually solidified nitro-glycerine, and having a closure or shell retaining member 14 shown in detail in Fig. 2. The shell and closure are lowered into the well by means of a cable 15 attached through a

50 coupling member 16 to supporting members 17 for the closure as shown. The cable passes over a supporting pulley 20 and thence to a reel 21 actuated by a pulley 22 and suitable power means, not shown. A depth indicator 23 of conventional construction indicates the amount of cable reeled

out. The cable contains two electric wires 24 and 25. Current is applied to these wires through the agency of two slip rings 26 and 27 on the reel, to which connection is made by two brushes 28 and 29 in circuit with a battery 30, a push button type switch 31 and an indicating instrument 32. Instead of the battery any other suitable source of current can be employed.

Referring to Fig. 2, the closure 14 contains a pair of latch members 33 urged inwardly by springs 34 and engaging corresponding cavities 35 in the upper thickened annular portion 36 of container 12. The two latch members are retained in position shown while the apparatus is being lowered into the well by two links 37 in pivoted relation to the two latch members as shown and pivoted at their junction 18 to a solenoid plunger 38 extending into a solenoid coil 39 supplied directly by leads 24 and 25 as shown. Upon energization of the solenoid, by closing switch 31, the links are pulled up past the center point so that springs 34 withdraw the latch members and release the container shell. The closure can then be drawn out of the well. To attach a new container shell to the closure, the closure is fitted on the shell and the latches are locked by reversing the solenoid coil current or by simply pushing down plunger 38.

Advantageously there is provided means for showing at the surface of the earth when the container has been released. These take the form of a small pin 40 retained in a bore 41 in the closure and resting on the lip of annulus 36. The pin is normally out of contact with a contact member 42 insulatedly supported at 43 on the closure. The pin and the contact member are connected in parallel with the solenoid by leads 45. Thus when the container shell leaves the closure, leads 24 and 25 are shortcircuited and this is exhibited by indicating instrument 32, as the resistance of the electrical circuit is less than when the solenoid is in circuit.

Fig. 3 shows a modified form of releasing device, applied to a closure 114. A plurality of solenoid coils 46 are provided (only one is shown) each having a cooperating plunger 47 with a latch portion 48 extending through the closure into cavities 49 in annulus 36. Upon energization of the solenoids the container is released.

Fig. 4 shows another modification, in which the hot wire principle is employed. A plurality of latch members 50 are provided, extending into cavities 49 as in Fig. 3 and urged inwardly by springs 34. The latch member is normally held outward by a bell-crank lever 51 pivoted to a fixed portion of the closure at 52 and having a roller 53 at its outer end engaging the rounded end 54 of the latch member. The lever rests on a stop 55 as shown and its opposite end is held in position, against the force of a spring 56, by a metal wire 57 adapted to expand on passage of a heating current therethrough. The wire is insulated from the lever at 58 and is supported through insulation 59 in a support 60 in the closure. Leads 24 and 25 are connected to spaced points on the wire. On energization of the leads the wire expands and lever 51 flies upwardly, releasing the latch.

Figs. 5 and 6 show a form of the invention adapted for releasing explosive directly into the well. As shown, a container 65 is provided, attached permanently to member 16 and the cable by supporting rods 17 and having a lower closure member 66 of approximately disk shape hinged at 67 to the shell. The closure contains a latch 75

member 50 of construction similar to the latch member in Fig. 4 and engaging a cavity 68 near the lower edge of the container. The latch member is normally retained in the position shown by a lever 69 pivoted to the closure member at 70 and having a roller 71 engaging the end of the latch member. A release is provided including a rotatable member 72 pivoted to the closure member at 73 and having a detent portion 74 loosely engaging the end of lever 69. Member 72 normally rests on a small support 75 on the closure. It is pivotally attached at 76 to a solenoid plunger 77 working in a solenoid coil 78 energized by wires 24 and 25. A mercury switch 79 is provided as shown, so connected that upon dropping of the closure the switch shortcircuits leads 24 and 25 so as to indicate at the top of the well that the closure has dropped. In Fig. 6 a simplified arrangement is provided, including a latch member 50 similar to the latch member of Fig. 4, normally retained in the position shown by a soft-iron lever 151 carrying a roller 53 and pivoted at 80 to the closure member 81. The lever is adapted to release the latch member upon energization of an electromagnet 82 arranged as shown with respect to the lever.

It will be clear that in all cases the apparatus includes means for positively preventing premature dumping of explosive, and electrical means for positively releasing the explosive when desired. The depth of the explosive shell is indicated at all times by the depth indicator, and should some obstruction in the well prevent lowering the shell to the desired level, the shell can be withdrawn intact and appropriate steps taken to remove the obstruction. The apparatus is embodied in the usual materials for oil well apparatus, such as steel and brass, and the cable can be of a conventional type used for lowering electrical well surveying apparatus and the like. Various types of explosives can be handled. For the sake of clarity the drawing is quite diagrammatic. The provision of suitable gaskets, sealing means, etc., to prevent leakage of the explosive is within the expected skill of those familiar with the art.

The explosive after being positioned according to the invention is exploded in any suitable manner, as by lowering a time bomb upon it, or dropping a weight, etc. Ordinarily a solid form of explosive is employed.

What I claim is:

1. An apparatus for placing a charge of explosive in a well under positive control from the top of the well comprising an explosive container of cross section such as to permit passage in a well and having an opening at one end of substantially the same area as the internal cross section of the container, a closure for the container opening, electrically operable latch means within the closure arranged to normally retain the closure in closed relation to the container, cable means constructed and arranged to suspend the container in a well, a source of electrical energy in circuit with the electrically operable latch means and circuit control means including leads extending up the cable and operable at the top of the well for controlling application of electrical energy to the latch means.

2. The apparatus of claim 1 wherein the container opening is at the bottom thereof whereby on release of the latch means the explosive charge is discharged from the container into the well.

3. The apparatus of claim 1 wherein the con-

tainer opening is at the top thereof and the closure is a separate element from the container, whereby on release of the latch means the container is left in the well.

4. The apparatus of claim 1 including in addition signaling means in said leads for indicating at the top of the well the moment of release of the releasing means.

5. An apparatus for placing a charge of explosive in a well under positive control from the top of the well comprising an explosive container of cross section such as to permit passage in a well, cable means constructed and arranged to suspend the container in a well, a releasable

holding member for coupling the explosive charge in said container to the cable means, electrical operable latch means associated with said holding member and normally positively engaging said container but operating under electrical energy to permit positive release of said explosive charge from said cable means, a source of electrical energy in circuit with the electrical operable latch means and circuit control means including leads extending up the cable and operable at the top of the well for controlling application of the electrical energy to the latch means.

GORDON C. MACDONALD.
